UNITED STATES PATENT OFFICE.

JOHN R. ROGERS, OF BROOKLYN, NEW YORK, ASSIGNOR TO MERGENTHALER LINOTYPE COMPANY, A CORPORATION OF NEW YORK.

TYPOGRAPHICAL MACHINE.

1,212,562.

Specification of Letters Patent. Patented Jan. 16, 1917.

Application filed February 24, 1915. Serial No. 10,165.

To all whom it may concern:

Be it known that I, JOHN R. ROGERS, a citizen of the United States, residing at Brooklyn, in the county of Kings and State 5 of New York, have invented certain new and useful Improvements in Typographical Machines, of which the following is a specification, reference being had therein to the accompanying drawing.

10 My invention relates to typographical machines, such as linotype machines of the general organization represented in Letters Patent of the United States No. 436,532, to O. Mergenthaler, wherein circulating matrices are released from a magazine in the order in which their characters are to appear in print and then assembled in line, the composed line transferred to the face of a mold, the mold filled with molten metal to 15 form a slug or linotype against the matrices which produce the type characters thereon, and the matrices thereafter elevated and returned through a distributing mechanism to 20 the magazine from which they started.

25 More particularly, it relates to that class of machines in which are employed type or matrices provided with two or more superposed characters, and devices by which the vertical position of the type or matrices in

30 the composed line may be varied so that each will present one or another of its characters in operative position, as demanded. The matrices when thus assembled at different levels are carried in this condition to 35 the casting mechanism, and are subsequently brought to a common level preparatory to distribution. Various mechanisms have been employed to effect the leveling of the matrices, one form being shown and de-

40 scribed in my previous Letters Patent No. 833,256, wherein a pair of inclined blades are located in the stationary upper transfer channel in position to engage the elevated matrices in the line, as the latter is transferred from the first elevator, and thus to 45 depress them to the level of the lower matrices.

My present invention is concerned principally with this method of leveling and 50 aims to secure the same result in a simplified and convenient manner. As is well known, the first elevator is ordinarily provided at its open end with a pair of retaining pawls which engage behind the last matrix in the

line and prevent its displacement therefrom 55 during the movements of the elevator. Specifically, I propose to construct these retaining pawls of such form that they not only serve to hold the line within the elevator, but in addition act upon the matrices 60 as they are transferred therefrom and bring them to a common level.

In the accompanying drawing, I have shown my invention in preferred form and by way of example and as applied to a linotype machine, but obviously many changes and variations may be made therein, and in its mode of application, which will still be comprised within its spirit.

Generally speaking, I desire it to be understood that I do not limit myself to any specific form or embodiment, except in so far as such limitations are specified in the claims.

Referring to the drawing: Figure 1 is a 75 front elevation, partly broken away, of the first elevator and intermediate channel of a linotype machine, having my invention applied thereto; Fig. 2 is a similar view showing the first elevator in operative relation 80 to the second elevator; Fig. 3 is a section on the line 3—3 of Fig. 2; and Fig. 4 is a detail-view.

In the accompanying drawing, I have shown only such parts of the machine as 85 are necessary to an understanding of my invention. The other parts may be of usual construction, such as illustrated in the Mergenthaler Patent No. 436,532, before referred to, or as embodied in the commercial 90 linotype machine.

The type or matrices X after being composed in line are transferred through the intermediate channel A to the first elevator B, which, after presenting them to the casting mechanism, rises to the position shown in Fig. 2, when the matrices are moved from the elevator by the transfer device or pusher C into the upper transfer channel F and onto the toothed bar D¹ of the second elevator D, which then carries them upward 100 for distribution into their proper magazine, all in the usual way. Referring to Fig. 1, it will be noted that the intermediate channel A is formed with ledges A¹ and A², and that the first elevator B is also formed with ledges B¹ and B², the latter ledges registering with the former, when the parts are in 105

the position shown, so as to provide continuous tracks upon which the matrices may be supported at different levels in their transfer through the machine. The ledges 5 A^1 and B^1 engage beneath the upper ears of the matrices standing at the lower level, while the ledges A^2 and B^2 engage beneath the lower ears of the matrices standing at the upper level. Similarly, the upper transfer channel F is formed with ledges F^1 10 adapted to register with the upper ledges B^1 of the first elevator, when the latter occupies the position shown in Fig. 2, so as to provide a continuous supporting track for the matrices as they are transferred from the elevator onto the toothed bar D^1 .

In accordance with my invention, the first elevator B is provided at its open end with a pair of pawls E , which are located in recesses B^3 in the side walls of the elevator 20 and are pivotally mounted upon transverse studs E^0 so as to be movable vertically. Arranged beneath the rear ends of the pawls are springs E^3 tending to lower their forward ends to the position shown in Fig. 4, pins E^4 fixed to the walls of the elevator acting to arrest the pawls in this position. The forward portions of the pawls are offset, as at E^5 (see Fig. 3) so as to overlie the matrices, and are formed with inwardly inclined surfaces E^1 to engage behind the last matrix in the composed line and hold it in proper position (see Fig. 4). The forward portions of the pawls are also formed with outwardly inclined surfaces E^2 , which are 30 adapted to be engaged by the matrices as they are transferred into the first elevator from the intermediate channel, and thus cause the pawls to move vertically (as shown by dotted lines in Fig. 1) against the action of their springs E^3 and permit the passage of the matrices thereunder. Similarly, when the matrices are transferred from the first elevator into the upper transfer channel F , they will engage the inclined surfaces E^1 of the pawls and move them vertically. Since, however, I propose to rely upon the inclined surfaces E^1 to depress the elevated matrices to the level of the lower ones during their 40 transfer from the elevator, means are provided to limit the upward movement of the pawls at such time. In the present instance, I employ for this purpose a forked member G located in the fixed framework and having a pair of prongs G^1 to project into the recesses B^3 of the elevator, when the latter arrives at its uppermost position and arranged to be engaged by the pawls as they are elevated by the matrices during their 45 transfer from the elevator (see Fig. 2).

The operation of the parts will now be clear. When the first elevator B is empty and in receiving relation to the intermediate channel A , the pawls E occupy the position shown in Fig. 4. As the composed

line is transferred into the elevator, the matrices engage the inclined surface E^2 of the pawls and lift them against the action of their springs E^3 , the extent of such lifting being governed by the constitution of the composed line, that is to say, according to whether the matrices all stand at the same level or at different levels therein. If the matrices all stand at the same level, then after the composed line enters the elevator, 70 the pawls are immediately returned to their original position (as shown in Fig. 4) with their inclined surfaces E^1 engaging behind the last matrix in the line. If, however, the last matrix in the composed line is standing 75 at the upper level, the pawls will occupy the position shown by full lines in Fig. 1. The first elevator B now descends to present the line to the casting mechanism and subsequently ascends to carry it into registry with the upper transfer channel F , at which time the transfer device C moves it from the elevator into the channel. During such transfer, matrices standing at the lower level, engage the inclined surfaces E^1 of the 80 pawls and merely raise them sufficiently to permit their passage thereby. However, any matrices standing at the upper level tend to lift the pawls to a greater extent, but this tendency is resisted and overcome by the 85 engagement of the pawls with the prongs G^1 of the fork G , the pawls being thus maintained in a substantially rigid condition and in such position that their inclined surfaces E^1 engage the elevated matrices, as they 90 are successively slid off their sustaining ledge B^2 , and positively depress them to the level of the lower matrices, when they may pass therewith along the ledges F^1 of the upper transfer channel F and onto the 95 toothed bar D^1 of the second elevator D . (See Figs. 2 and 3.)

It will be understood that while I have designed the pawls E to subserve the two functions noted, they may be employed to 100 perform one or another thereof independently, as it will be apparent that they may be used advantageously for either purpose, depending upon the style of machine to which they are applied.

As previously stated, I have shown my invention merely in preferred form and by way of example and it will be obvious that many modifications and alterations therein, and in its mode of application, will suggest 110 themselves to those skilled in the art without departure from its scope.

Having thus described my invention, its construction and mode of operation, what I claim and desire to secure by Letters Patent 125 of the United States is as follows:

1. In a linotype machine, the combination of the first elevator provided with means to sustain the type or matrices at different levels therein, a device to transfer them 130

- therefrom, and a movable member carried by the elevator and having an inclined surface to engage the type or matrices during their transfer therefrom and bring them to 5 a common level, the said member being provided with an oppositely inclined surface which is engaged by the type or matrices as they enter the elevator and thus displaced thereby.
- 10 2. In a linotype machine, the combination of the first elevator provided with means to sustain the type or matrices at different levels and also with a retaining pawl to hold them therein, and a device for transferring 15 the type or matrices from the elevator, the said retaining pawl acting upon the type or matrices to bring them to a common level during their transfer.
3. In a linotype machine, the combination 20 of the first elevator provided with means to sustain the type or matrices at different levels and also with a retaining pawl to hold them therein, and a device for transferring the type or matrices from the elevator past the retaining pawl, the said pawl being formed with an inclined surface to engage the elevated type or matrices during 25 their transfer and depress them to the level of the lower ones.
- 30 4. In a linotype machine, the combination of the first elevator provided with means to sustain the type or matrices at different levels and also with a movable retaining pawl to hold them therein, and a device for 35 transferring the type or matrices from the elevator past the retaining pawl, the said pawl being formed with an inclined surface to engage the type or matrices during their transfer and bring them to a common level 40 and also with an oppositely inclined surface adapted to be engaged by the type or matrices as they enter the elevator and thus be displaced thereby.
5. In a linotype machine, the combination 45 of the first elevator provided with means to sustain the type or matrices at different levels therein, a device for transferring them therefrom, a movable member carried by the elevator and having an inclined surface 50 which is engaged by the elevated type or matrices during their transfer so as to be displaced thereby, and a stop to limit the displacement of said member, the inclined surface of said member acting in the limited position thereof to depress the elevated matrices to the level of the lower ones.
6. In a linotype machine, the combination of the first elevator B having the ledges B¹ and B² to sustain the type or matrices at different levels and provided with the vertically movable pawls E having the inclined surfaces E¹ which are engaged by the type or matrices during their transfer, and the forked member G fixed to the framework and having its prongs G¹ arranged to limit 65 the vertical movement of the pawls, for the purpose described.
7. The first elevator provided at its open end with a spring-actuated line retaining pawl, the said pawl being mounted to move 70 vertically and having oppositely inclined surfaces which are engaged by the matrices as they enter and leave the elevator and thus cause the vertical movement of the pawl.
8. The first elevator B provided with the 75 pawl E pivoted between its ends and formed at its forward end with the oppositely inclined surfaces E¹ and E², and the spring E³ and stop E⁴ coöperating with the rear end of the pawl to hold it in normal position.
9. The first elevator B formed in its side wall with a recess and provided with the spring-actuated pivoted pawl E located in 80 said recess, the forward end of said pawl being formed with the oppositely inclined surfaces E¹, E², and offset with respect to the remaining portion so that the inclined surfaces may be engaged by the matrices as they enter and leave the elevator, for the purpose described.
- In testimony whereof, I have affixed my signature in presence of two witnesses.
